UNITED STATES PATENT OFFICE.

HARRISON H. TAYLOR, OF DETROIT, MICHIGAN, ASSIGNOR TO THE MICHIGAN RADIATOR AND IRON MANUFACTURING COMPANY, OF SAME PLACE.

MACHINE FOR CUTTING RIGHT AND LEFT THREADS ON NIPPLES.

SPECIFICATION forming part of Letters Patent No. 403,791, dated May 21, 1889.

Application filed September 25, 1888. Serial No. 286,352. (No model.)

To all whom it may concern.

Be it known that I, HARRISON H. TAYLOR a citizen of the United States, residing at Detroit, county of Wayne, and State of Michigan, have invented certain new and useful Improvements in Screw-Threading Machines; and I declare the following to be a full, clear, and exact description of the invention, such as will enable others skilled in the art to which it appertains to make and use the same, reference being had to the accompanying drawings, which form a part of this specification.

My invention relates to certain new and useful improvements in screw-threading machines, and is more particularly designed for simultaneously cutting right and left hand screw-threads upon a nipple, the threads being cut from the center toward the extremities to constitute a right and left hand screw-threaded nipple for uniting simultaneously adjacent hubs of radiator-loops, and any other uses to which such a nipple is found adapted.

My invention consists of the combinations of devices and appliances illustrated in the accompanying drawings, and more particularly hereinafter described, and pointed out in the claims.

In the drawings, Figure 1 is a front end elevation of the device embodying my invention. Fig. 2 is a side elevation. Fig. 3 is a plan view; and Fig. 4 is a vertical section, on the line $x-x$, Fig. 1.

I carry out my invention as follows:

35 A represents any suitable support.

A' A^2 respectively represent sliding beds engaged upon said support, each bed carrying a rotatable spindle (shown at A^3 A^4) provided with a driving-gear, a a' , and at their adjacent ends with a multiple cutter, a^2 a^3 , the one cutting a right and the other a left hand thread. The sliding beds are screw-tapped, as at a^4 a^5 , to receive a connecting-spindle, A^6 , screw-threaded toward its extremities to engage the sliding beds, the union of the spindle with one of the beds being a right and with the other bed a left hand screw-connection, the construction being such that when the spindle is rotated said beds A' A^2 , respectively, will have opposite move-

ments in the support A, thereby reciprocating the cutters a^2 a^3 toward and from each other, the sliding beds each carrying its respective spindle with it as it is moved to and fro. I prefer to recess each bed, as shown at 55 a^6 , to receive a portion of the spindle, the extremities of the beds alone being screw-tapped.

B represents a chuck of any suitable construction for carrying the nipple. 60

While I do not confine myself to any specific construction of the chuck, I prefer that it should be provided with expansible jaws to interiorly engage the nipple. Accordingly, I have shown a chuck of this description in the 65 drawings, in which B' is a tubular spindle located in a laterally-movable block, A⁵, and having a rotatable engagement therein. The tubular spindle is provided at one extremity with movable jaws b, having spindle C sleeved 70 therein and extending through the tubular spindle, the spindle C being constructed with wedge-shaped grooves c adjacent to said jaws. Such a chuck is shown in my patent, No. 331,167, granted November 24, 1885. 75

The tubular spindle B' is provided with a rotating gear, b', and the spindle C has a screw-tapped engagement with an operating-handle, C', whereby the jaws may be expanded and permitted to contract as the handle is 80 turned to or fro upon its spindle. By this means it is evident a nipple, D, may be interiorly engaged by the expansible chuck and held firmly to the cutters.

E denotes a driving-pulley mounted upon 85 the driving-shaft E', journaled in the support and extending across the machine, being provided toward the extremity opposite the pulley with a pinion, e, meshing with the corresponding gear a of the spindle A³, a pinion, 90 e', upon the driving-shaft also meshing with the gear a' upon the spindle A⁴. By this mechanism the multiple cutters are driven.

F represents an additional driving-pulley upon the driving-shaft F', said shaft being 95 provided with a sprocket-wheel, F², connected by a sprocket-chain, F³, with a sprocket-wheel, G, upon a shaft, G', provided with a worm, g, meshing with a worm-gear, H, loosely mounted upon the spindle A⁶, and provided in turn 100

with a gear, H' , meshing with the gear b' , located upon the tubular spindle B' . The spindle A^6 has a screw-tapped engagement with an operating or tightening handle, I , as shown at i .

5. J is a tightening device engaging the chain F^3 .

In order to engage and remove the nipple readily, it is evident that the chuck should be laterally movable, so as to clear the nipple from the cutters. It is for this reason that the tubular spindle of the chuck is engaged in a sliding block, A^5 . To manipulate said block to move it laterally, a screw-cut shaft, 15 K , is engaged therewith, as shown at k , said shaft also having a screw-tapped engagement with a hanger, K' , and provided with an operating-handle, k' .

L is an adjustable stop to regulate the 20 movement of the bed. Should nipples of different sizes be desired to be threaded, the stop can be moved so as to allow the proper lateral adjustment of the chuck. By rotating the handle k' the block will be laterally moved 25 in a corresponding manner.

M represents a tightening-screw for locking the screw K in any given position to hold the block A^5 in place.

The worm-gear H has a frictional engagement with the gear H' , as shown in Fig. 4. 30 As the worm-gear is loosely mounted upon the connecting-spindle A^6 , serving as a feed-screw, it is evident that by loosening the handle I said worm-gear may continue to rotate; 35 but the reciprocation of the sliding beds A' A^2 and the rotation of the chuck will cease. They are thus thrown out of operation. When it is desired to throw them into operation, the handle I is tightened up, bringing 40 the gear H into frictional contact with the gear H' . To return the cutters together, the driving-power will be reversed.

The operation of the machine will now be understood.

45. What I claim is—

1. In a screw-threading machine, the combination, with a support, of rotatable reciprocating cutter-spindles located end to end, and a rotatable laterally-movable chuck to hold 50 the work adjacent to the cutters, substantially as set forth.

2. In a screw-threading machine, the combination, with a support, of cutter-spindles, each having a rotatable and reciprocatory 55 movement in said support and located end to end, a rotatable chuck to hold the work adjacent to the cutters, and mechanism to simul-

taneously reciprocate and rotate such spindles, substantially as set forth.

3. In a screw-threading machine, the combination, with a support, of rotatable cutter-spindles located end to end and provided each with a multiple cutter, a rotatable chuck to hold the work, and means to feed the cutters apart when in engagement with the work, substantially as set forth.

4. In a screw-threading machine, the combination, with a support, of sliding beds A' A^2 , connected with a feed-screw having a right and left hand engagement with said beds, 70 worm-gear to rotate said feed-screw, and mechanism to actuate said worm-gear, said beds provided each with a cutter-spindle, substantially as set forth.

5. In a screw-threading machine, the combination, with a support, of sliding beds A' A^2 , cutter-spindles journaled in said beds, a rotatable chuck to engage the work, and mechanism to simultaneously reciprocate said beds and rotate said spindles, substantially as set forth.

6. In a screw-threading machine, the combination, with a support, of sliding beds A' A^2 , rotatable cutter-spindles journaled in said beds, a feed-screw having a right and left hand engagement with said beds, a chuck to hold the work, and mechanism to rotate said feed-screw and said chuck, substantially as set forth.

7. In a screw-threading machine, the combination, with a support, of a rotatable chuck to engage the work, sliding beds connected with a feed-screw having a right and left hand screw-tapped engagement therewith, cutter-spindles journaled in said beds, worm-gear to 95 rotate said feed-screw, and mechanism to rotate said worm-gear, substantially as set forth.

8. In a screw-threading machine, the combination, with a support, of sliding beds A' A^2 , a feed-screw having a right and left hand screw-tapped engagement with said beds, a worm-gear loosely mounted upon the feed-screw, a handle having a screw-tapped engagement with said screw, whereby the gear may be tightened thereupon, and a worm 105 meshing with said gear, substantially as set forth.

In testimony whereof I sign this specification in the presence of two witnesses.

HARRISON H. TAYLOR.
